UNITED STATES PATENT OFFICE.

ADOLPHE LE MOULT, OF NEW YORK, N. Y.

DESIGN FOR A FLORAL STAND.

SPECIFICATION forming part of Design No. 15,092, dated June 24, 1884.

Application filed November 28, 1883. Term of patent 33 years.

To all whom it may concern:

Be it known that I, ADOLPHE LE MOULT, a citizen of the United States, residing in the city of New York, in the county and State of New York, have invented and produced a new and original Design for a Floral Stand, of which the following is a specification, and reference being had to the accompanying drawings, forming part thereof.

10 The figure shown in the drawing is a full view of the whole of my design. This consists in representing a balloon with gondola attached, resting on a bed of flowers, appearing as if about rising in the air.

15 My design represents a balloon, B, rising from the center of a round flat basket, A, of sufficient size, having four curved standards, a, which merge, as indicated at d. A conven-

tional gondola, C, is shown midway between the basket and the balloon, having curved and pointed ends. The basket A has a diamond-shaped ornamentation extending entirely around the same, that adds materially to the tasteful appearance produced by the whole design. 20

What I claim is—

The design for a floral stand, the same consisting of the representation of the balloon B, the round flat flower-basket A, and the gondola C, as herein shown and described. 25

ADOLPHE LE MOULT.
